UNITED STATES PATENT OFFICE.

HARRY L. McNEIGHT, OF FREDONIA, NEW YORK.

WAR GAME.

1,281,040.

Specification of Letters Patent.

Patented Oct. 8, 1918.

Application filed January 16, 1918. Serial No. 212,006.

To all whom it may concern:

Be it known that I, HARRY L. McNEIGHT, a citizen of the United States, residing at Fredonia, in the county of Chautauqua, and 5 State of New York, have invented certain new and useful Improvements in War Games, of which the following is a specification.

This invention relates to an improved 10 game and has as its primary object to provide a device of this character wherein the game board employed will embody a map showing the principal countries of central Europe and wherein the said countries will 15 be divided into opposing or belligerent groups each having an army represented by the game pieces employed so that the players of the game in each moving the game pieces to capture the game pieces or army of the 20 opposing player will be supplied with the incentive of winning for the group of nations represented by such player.

The invention has as a further object to 25 provide a game which will furnish scientific and entertaining amusement and which will also, at the same time, provide an interesting and easy way of learning the relative location of the different countries of central Europe, the location of their principal 30 cities and fortifications, as well as the courses of the various principal rivers of the said countries.

And the invention has as a still further object, in this connection, to provide a game 35 wherein the game board employed will prove of real practical value as a reference map for supplying geographical information concerning the principal central European countries.

40 Other and incidental objects will appear as the description proceeds. In the drawings wherein I have illustrated the preferred embodiment of the invention, and wherein similar reference characters designate corresponding parts throughout the several views:

Figure 1 is a plan view of my improved game board showing the manner in which the playing surface of the board is adapted 50 to provide a map of the principal countries of central Europe,

Fig. 2 is a fragmentary diagrammatic view showing the manner in which the neutral areas of the board are indicated,

55 Fig. 3 is a view similar to Fig. 2, and showing the manner in which the area of

one group of belligerent nations is indicated, such group being designated the Entente,

Fig. 4 is a view similar to Fig. 3, and 60 showing the manner in which the other group of belligerent nations is indicated, this group being designated as the Central Powers,

Fig. 5 is a diagrammatic view showing 65 the manner in which the capitals of the various nations are designated,

Fig. 6 is a perspective view showing a specimen of one of the sets of game pieces 70 employed, and

Fig. 7 is a perspective view showing a specimen of the other set of game pieces employed.

In carrying out the invention I employ a preferably oblong game board 10. This 75 game board may be constructed of cardboard or other suitable material and is preferably formed to fold along a medial longitudinal line. The board may, of course, be varied in size, as found most desirable. The playing surface of the board is laid off in 80 squares after the manner of an ordinary checker board and imprinted or otherwise traced upon the said surface of the board is a map particularly showing the principal 85 countries or nations of central Europe. The capitals of these countries are indicated by a designating mark, as shown in Fig. 5 of the drawings. The principal cities and fortifications of the said countries are also 90 preferably indicated, as are the courses of the various rivers. However, to avoid confusion, I have, in the present instance, only shown the capitals of the majority of the 95 countries and a few of the principal cities.

For the purposes of the present game certain of the countries are divided into opposing or belligerent groups while certain other of the countries are designated as neutral countries. The countries of one belligerent group are indicated as shown by the 100 diagram of Fig. 3, and for convenience are designated as the Entente. The countries comprising such group include, as will be observed, Great Britain, France, Italy, Portugal, 105 Russia, Serbia, Montenegro, Albania, Greece, Sicily, Sardinia, Corsica, Morocco, Algeria and Tunis. The area of these countries is preferably colored yellow, or other distinctive color. The countries of the 110 other belligerent group are indicated as shown by the diagram of Fig. 4, and for con-

venience, are designated as the Central Powers. The countries included in the Central Powers are, as will also be observed upon reference to Fig. 1, Germany, Austria-
5 Hungary, Bulgaria and Turkey. The area of the countries of the Central Powers is preferably colored pink or some other distinctive color different from the color of the area of the Entente nations. The countries
10 of the neutral group are indicated as shown by the diagram of Fig. 2. The neutral group of countries includes Switzerland, Denmark, Norway, Sweden, Holland and Spain. The area of this group of countries
15 is preferably colored green or some other distinctive color different from the colors of the areas of the belligerent groups respectively, while the borders of the countries of the neutral group are also preferably colored
20 order red to further identify the countries of the said group.

Within the area controlled by the group of Entente nations, certain of the squares of the game board are identified by a plurality of circles or other approved mark to indicate the initial positions for the game pieces representing the army of such group. The circles referred to are indicated at 11 and preferably the said circles are of a distinctive identifying color. Within the area controlled by the group of countries designated as the Central Powers, certain of the squares of the game board are identified by a plurality of circles or other approved mark designating the initial positions for the game pieces representing the army of the Central Powers. The latter circles referred to are indicated at 12. In order to distinguish the circles 12 from the circles 11,
40 I have, in Fig. 1, shown the circles 12 within a surrounding ring. The circles 12 are of a distinctive identifying color different from that of the circles 11. In this connection, it should be observed that there are
45 twenty-five of the circles 11 and also an equal number of the circles 12. The number of the circles, in each instance, will depend, of course, upon the maximum number of game pieces used to represent the armies
50 of the countries of the belligerent groups.

The game pieces employed are preferably small disks, as shown in Figs. 6 and 7 of the drawings. In Fig. 6 I have shown a typical one of the game pieces belonging to the Entente group of countries. These game pieces are indicated by the reference numeral 13 and are hatched, as shown in this figure in order to distinguish in the drawing from the game pieces of the group of countries
55 designated as the Central Powers. Twenty-five of the game pieces 13 are preferably employed and these game pieces are given a distinctive identifying color such as green. In Fig. 7 I have shown a typical one of the
60 game pieces representing the army of the
65

group of countries designated as the Central Powers. Such game pieces are indicated by the reference numeral 14 and are hatched as shown in Fig. 7 to distinguish in the drawing from the game pieces 13. The 70 game pieces 14 are given a distinctive color different from that of the game pieces 13, such as red. Twenty-five of the game pieces 14 are also preferably employed. However, it is to be understood that the number of 75 game pieces representing the armies of the different opposing groups of countries may be varied as found most desirable.

In playing the game, all of the game pieces 13 are initially placed within the squares of 80 the game board designated by the circles 11. In like manner all the game pieces 14 are disposed within the squares of the game board designated by the circles 12.

These game pieces then represent the opposing armies of the countries of the belligerent groups and the players may begin moving the game pieces, one player, of course, representing one group of countries or the Entente, and the other player representing the other group of countries or the Central Powers. In moving the game pieces the object of each player is to so dispose and shift his game pieces or army upon the board as to capture the game pieces or 90 army of the opposing player and thus clear the board of such opposing army. Each player in turn moves one game piece at a time and each game piece can be moved only one square at a time but may be 100 moved in any direction on the board or, in other words, either forward or back or cross-wise in either direction. All of the squares taken in or touched by the boundary of a neutral country will be considered as neutral squares and, in playing the game, the game pieces must be moved around such neutral squares under penalty of being considered as interned to be consequently removed from the board, upon entering such neutral 105 squares. The game pieces of each army are captured by being jumped by a game piece of the opposing army. A player may jump any of his game pieces in any direction and may jump any number of his opponent's 110 game pieces provided that there are intervening empty squares in which to alight the game piece being used to jump and further provided, of course, that such game piece being used to jump will not alight in a neutral square. The opponent's game pieces so jumped will be immediately removed from the board. When a player is in a position to capture an opposing game piece by jumping, but in so doing enters a neutral square, 115 such player must remove his opponent's game piece so jumped, but as a penalty for having entered the neutral square, must also remove the game piece entering the said square. In some instances it will be seen 120

that a player might find it of advantage to thus lose a game piece if, by so doing, he were able to capture two or more of his opponent's game pieces.

5 In any instance where a player might jump one of his game pieces in two or more directions to capture one his opponent's game pieces, such player shall be entitled to choose the particular direction in which he

10 shall jump his game piece, and this without regard as to whether by jumping in one direction the player would be enabled to capture only one opposing game piece or by jumping in a different direction he would be enabled

15 to capture more than one opposing game piece. Should a player have a game piece in position to capture a game piece belonging to the opposing player and fail to so capture the oposing game piece, the player shall be

20 considered to forfeit the game piece which should have been moved to effect the capture and the said forfeited game piece shall be immediately removed from the board. The player who first captures all of his oppo-

25 nent's game pieces or forces the game pieces of his opponent into such position that they cannot be played, will be considered to win the game and, it will be seen that since the opposing game pieces represent the respec-

30 tive armies of the countries of the belligerent groups as designated upon the game board, a particular incentive will be furnished each player to win the game. Furthermore, it will be seen that in playing the

35 game the geographical features of the several countries illustrated by the map upon the game board, will unavoidably be brought to attention. Consequently the game will provide an easy and interesting way of

40 learning the relative geographical location of the various countries shown as well as the location of their capitals, principal cities, fortifications, or other places of strategical importance. Also, in this connection it will

45 be seen that the map of the game board will prove of real practical value as a reference

map for gaining detailed information concerning the area shown.

Having thus described the invention, what is claimed as new is:

1. A game of the character described including a game board having a playing surface marked off in playing spaces and bearing a map showing the boundaries of a plurality of countries, the said countries being divided into groups and the countries of one of the groups being designated as neutral areas upon the board.

2. A game of the character described including a game board having a playing surface marked off in playing spaces and bearing a map showing the boundaries of a plurality of countries, the said countries being divided into groups including opposing groups of countries and a neutral group of countries indicating neutral playing spaces upon the board.

3. A game of the character described including a game board having a playing surface marked off in playing spaces and bearing a map showing the boundaries of a plurality of countries, the said countries being divided into groups including opposing groups of countries having their areas distinguished upon the board by a common identifying color for the countries of each of such opposing groups, and a neutral group of countries having their areas distinguished upon the board by a common identifying color different from the color of each of said first-mentioned groups of countries.

4. A game of the character described including a game board having a playing surface marked off in playing spaces and bearing a representation of the geographical boundaries of countries belligerent and a neutral country, the area of the neutral country bearing a distinguishing color and the border thereof bearing a different color.

In testimony whereof I affix my signature.
HARRY L. McNEIGHT.
